UNITED STATES PATENT OFFICE.

ALBERT LEVKOWITS, OF NEW YORK, N. Y.

GOLF APPARATUS AND THE LIKE.

Application filed March 27, 1923. Serial No. 628,021.

My invention relates generally to the game of golf and has specific reference to a combination of apparatus, topographical maps, and protractor with which it is possible to produce or simulate conditions on a golf course to an extent that a game of golf may be played in a limited space with substantially the same accuracy as it is played on any standard golf course.

The invention has for its principal objects to provide, first, an instrument carrying a regulation golf ball which when projected by a blow from a club will cause the instrument to register distance, height and deflection of flight of the ball; second, a topographical map of any golf course comprising a separate sheet for each hole of the course and showing all of the true conditions of the course; third, a protractor on the arc of which may be calculated a scale corresponding to the distance, height and deflection scales on the measuring instrument, such scales being substantially the same as that to which the map itself is drawn; and fourth, a series of devices designed to receive the ball during the game, whereby certain conditions encountered in the course may be effectively reproduced, i. e. high grass, sand holes, etc.

The present invention is illustratively exemplified in the accompanying drawings, in which Figure 1, is a plan view of my improved measuring instrument; Figure 2, is a longitudinal sectional view through the same; and Figure 3, is a side elevational view of the outer end of the instrument showing the apparatus and scale for measuring the height of the ball during flight; Figure 4, is a plan view of my improved protractor; Figure 5, is a view of one of the sheets of the topographical map of the golf course showing by way of example a few of the possible plays in the game and the manipulation of the protractor to determine the playing conditions preceding and subsequent to each stroke, Figure 6, shows a box containing several of the devices used to receive the ball and to represent the conditions in which a ball may be placed during the play, i. e. sand traps, high grass etc.; and Figure 7, is a side elevational view of the arrangement used to represent high grass.

Referring now to the drawings and particularly to Figures 1 to 3, 10 designates a wall or weighted floor platform bracket

having a forwardly projecting arm 10^a provided with a vertically disposed bearing surface 11 adjacent its free end. Mounted to swing through a plane substantially at right angles to the plane of the bracket 10 and about the bearing 11 is a supporting bracket 12 comprising an annular portion 13 having the central opening to receive the bearing 11 and a radially projecting arm 14 provided with an interiorly threaded socket 15. The socket 15 is adapted to receive the threaded end of a tubular drum 16 which is provided with four longitudinally disposed slots 17 cut through longitudinally of the drum and projecting from the outer end thereof to a point about midway of its length. Telescopically supported in the drum 16 and extensible through the outer open end thereof is a second tubular drum 18 having its inner end closed and provided with radially projecting lugs 19 which extend through the slots 17 and are adapted to be guided throughout the length of the latter in the operation of the measuring device to measure the distance a ball will travel in its flight. The outer end of the drum 16 is exteriorly threaded to receive an annular collar 20 which prevents the inner drum 18 from being drawn outwardly and free of the drum 16. Disposed loosely about the drum 16 and arranged between the lugs 19 and the collar 20 is an indicator ring 21 comprising an annular member provided with a beveled forward edge adapted to register with a series of graduations 22 disposed on opposite sides of the uppermost slot 17, such graduations being separated from each other along the longitudinal axis of the drum 16 a distance equal to some general scale to which a map of the golf course is laid out, as hereinafter described.

Inasmuch as graduations designated 22 are disposed longitudinally of the axis of the drums 16 and 18 it will be apparent that any readings taken from this scale will be for movement of the drum 18 in an axial direction which indicates straight outward travel of the ball in its flight and in order to offer the proper resistance to such movement of the drum 18 the inner end thereof having the lugs 19 is provided with an eye 23 which receives one end of a coiled spring 24, the opposite end being connected to a plug 25 received into the end of the drum 16 embraced by the socket 15.

The outer end of the drum 18 is provided

with an upright flat projection 26 disposed transversely across the end, the projection 26 having a curved free end and a central opening 27 therein to pivotally support a pin 28, which is adapted to project from opposite sides of the projection 26, and which projects through slots 29 of U-shaped strap 30. The closed end of the strap 30 extends over the edge of the part 26 and is provided with an opening 31 to receive one end of a string 32, the opposite end of which is embedded in a regulation golf ball 33, as shown in Figure 2. The strap 30 may be adjusted with respect to the pin 28 and the free ends of the former are provided with pointers 34 which move through an arc on the projection 26 indicating the relative height traversed by the ball in its flight, the arc being designated by suitably spaced radial graduations 35, as shown in Figure 3. The adjusted position of the strap 30 with respect to the pin 28 is held fixed by a thumb screw 36 which tends to clamp the strap and the pin together. By means of the relative cooperation of the parts just described the distance and height attained by the ball in its flight will be registered upon the scales or dials 22 and 35, respectively.

30 The third possible condition which the ball may assume in its flight is measured by the distance the line of travel of the ball is deflected sidewise from an axial line projecting from the longitudinal axis of the instrument. Such a condition is indicated by means of an apparatus comprising an upright integral lug 37 carried by the arm 13 of the bracket 12 and a pair of relatively adjustable plates 38 and 39. The plates 38 and 39 comprise disc-shaped members loosely mounted on step bearings 40 and 41 arranged one above the other on the end of the arm 10 and above the bearing surface 11. The peripheries of the plates coincide with the inner edge of the lug 37 and both plates are provided with radially projecting indicators 42, the uppermost plate 39 having its indicator disposed in the path of the lug 37 as it moves in an anticlockwise direction.

40 while the lowermost plate 38 carries its indicator in the path of the lug 37 as it moves in a clockwise direction. A dial 43 is arranged in an arc upon the face of the annular portion 13 of the bracket 12 and comprises a series of graduations which bear a definite relation to the possible number of degrees of lateral deflection of the ball in its flight, i. e. such degrees as may be measured on both sides of the axis of the instrument and indicated on the dial by zero. To counteract inertia of the moving instrument about its pivot bearing 11, a pair of adjustable springs 44 are disposed on opposite lateral sides of the device and connected at one of their ends to the rearwardly disposed

face of a pair of wings 45 integral with the socket 15, the opposite ends of the springs being attached to nipples 46 which are capable of adjustment over studs 47 carried by the face of the wall bracket 10 and by adjustment thereof the tension or compression of the springs 44 may be equalized to hold the apparatus in proper initial position.

Referring now to the protractor shown particularly in Figure 4, 50 designates the protractor proper which comprises a piece of transparent material, such as celluloid, having a center opening 51 to receive a centering pin. The protractor is semi-circularly shaped and provided about its uppermost segment with a marginally projecting strip 53 extending on both sides of a perpendicular center line projected upwardly from the center opening 51. The strip 53 extends over an arc which is substantially 100 degrees of the circle about the point 51 and which is divided into indicated graduations 54 measuring 5 degrees between each, so as to bring the graduation designated 50° on the said perpendicular line. The periphery of the protractor at the graduation designated 50° projects outwardly along the perpendicular line to provide a straight edge 55, the opposite edge of the projecting portion is defined by a gradual curve which connects with the curve of the strip 53 adjacent the right end thereof. For convenience in future reference let the point or opening 51 be referred to as the zero point and radially disposed from this zero point are a series of straight slotted openings 56, one edge of each slot being provided with a scale 57. In the present embodiment of the invention I have shown the protractor as being divided by the slots 56 into six sectors which gives seven scales 57. These scales 57 are divided into an equal number of graduations but in each scale the graduations are spaced apart from each other a different distance. The distance between the markings of one scale and those of another indicate the relative heights the ball must take in its flight to make certain plays, as hereinafter described.

The topographical map of the golf course over which the game is to be played is divided into eighteen sheets, each sheet showing the playing course for one of the eighteen holes. Figure 5 shows by way of illustration one of such sheets, designated 60, of a course on which is located the tee 61, the fairway 62, the green 63 and rough 64, and all the hazards such as bunkers 65, sand traps 66, lakes, brooks, out-of-bounds markings, etc. The sheets are preferably arranged in pad form with each succeeding sheet representing the next hole to be played.

In Figure 6, 70 denotes a box in which a section is set apart to contain material to represent grass, 71, a sand trap 72 and tall

grass 73. The tall grass 73 may be made by disposing upright resilient projections over a limited area of the box 70, with sufficient space in which to position the ball.

5 Other well known devices may be included in the set, such as putting holes, etc., which will practically enable a player to play a game of golf in a limited space either indoors or outdoors, exactly as it is played on 10 a standard golf course.

The game played with the apparatus just described may be carried out in the following manner, and it will be understood that while I am describing a few of the possible 15 plays over one sheet, or hole, all of the other sheets of the course may be played in a similar manner. The measuring instrument which is attached either by means of the wall or weighted floor platform plate, is in 20 a slack position and ball 33 rests upon improvised tee corresponding to the zero point or tee 61 on the map or sheet. The protractor 50 is then placed upon the sheet 60 so that the openings or zero point 51 may be 25 made to coincide with the tee 61 whereupon the push or centering pin 52 is driven into the opening 51 to provide a pivot about which the protractor 50 may swing. If the course from the tee 61 to the hole designated 30 67, may require several strokes, and the first drive as nearly as can be determined will be over unobstructed ground the exact distance to be traveled by the ball may be determined along the straight edge 55. For convenience 35 let it be assumed that an obstructed course of over 350 yards is presented in which case the player returns to the ball 33 and makes a drive and the ball is projected so as to effect movement of all of the indicators of 40 the measuring instrument.

When the pull has stopped, the inner drum 18 after being drawn out axially against the tension of the spring 24 will have returned to its initial or zero position, 45 but the indicating ring 21 will remain in its adjusted position, i. e. at a point on the scale 22 which indicates the maximum elongation of the spring 24 for that pull, such elongation of the spring 24 being proportional 50 to the horizontal component of the pulling force, which in turn is directly proportional to the horizontal component of the force with which the ball has been hit. Considering now only the forces acting in a 55 plane coincident with the vertical axis of the device, any pull on the strap 30 not in axial alignment with the drums will have a component tending to rotate the strap and such a component becomes zero when the 60 strap 30 has rotated about its pivotal center to a point where these lines coincide. The final position of the strap 30 indicates the direction of the pulling force in a vertical plane, and from the position of the pointer 65 34 relative to the dial 35 the exact trajectory

of the ball may be determined. Knowing the distance point and the angle of trajectory along a vertical plane the exact location of the ball determined by these two components considered may be determined. Therefore any reading of the dial 35 taken with the reading of the elongation of the spring on the scale 22 will correspond to a definite trajectory.

Inasmuch as the entire mechanism for 75 measuring distance and trajectory is freely mounted on the bearing surface 11, the mechanism itself will be free to rotate about this bearing, a condition which enables the forces acting on a plane horizontally disposed with respect to the axis of the drums 16 and 18 to be indicated. Considering now 80 only forces acting in this horizontal plane, any pull on the strap 30 that is not in the line from the point of attachment of the string to the center of the pin 28 will have a component tending to rotate the entire mechanism about the pivotal center of the bearing surface 11, this component becoming 85 zero when the axis of the mechanism has moved to a point where these lines coincide. The rotation of the lug 37 by this operation tends to revolve one or the other of the plates 38 and 39 through a space indicated 90 along the dial 43 by the position of the indicators 42. Therefore, the readings of the dials 43 and 35 and the scale 22, subsequent to a drive, gives the horizontal deflection, 95 height and distance of the flight of the ball.

In order to clearly understand just how 100 certain conditions in the plays of the game are determined it might be well to explain briefly just what the conditions are in the ordinary regulation game and then to explain further how these same conditions are 105 brought about and played by means of my invention.

Golf, as it is played outdoors on a golf 110 course, is a game in which a ball is hit from one definite point (called the teeing ground) to another definite point (called the cup) with clubs of various shaped heads in the least number of strokes. The playing ground along which the ball is played from the teeing ground to the cup is one unit of 115 a golf course and is numbered and called hole #1. A golf course consists of either 9 or 18 such units or holes.

The playing course, from the teeing 120 ground to the cup, consists of the "fairway" on which the grass is cut short so that when the ball lies on the fairway, it can be hit with any club with no resistance from the grass; the "rough", which borders the fairway on all sides, and upon which the grass is not cut and upon which may be trees and bushes or shrubs, and the "hazards". The "hazards", which may be located either in the fairway or the rough are (1) "sand traps" or pits which are filled with sand (2) 125

water (3) "bunkers" or mounds which rise above the surrounding ground to a height of from one to ten feet. These hazards are so placed as to penalize strokes that, according to the hazards, i. e. (1) are too long or too short (2) are deflected too much from the line along which it is desirable to hit. (3) do not have a sufficiently great angle of departure or angle of descent of trajectory.

10 The cup is located on what is called the "green" upon which the grass is cut so short and is so uniform, that a ball may be rolled along it and not be deflected from a straight line except by undulations in the ground 15 itself.

15 The infinite number of angles of departure, from the angle of departure of the lowest ball that can be hit that will leave the ground, to the greatest possible angle of departure, I have divided into six groups and any reading of the angle of departure scale on the indicating device will fall into one of these six groups. These six groups I have numbered in order one to six, number 20 25 one being the group of the smallest angle of departure.

20 I have, for convenience, called a ball the angle of departure of whose trajectory falls into group 1, a "height 1 ball" and a ball the angle of departure of whose trajectory falls into group 2 a "height 2 ball" etc.

25 For each group, the average angle of departure has been taken and the relation between the carry and the roll of a ball hit 30 with that angle of departure, has been obtained; and any ball in any height group will be considered to have the same rate of carry and roll as that obtained for the average for the group.

35 40 When a ball is hit into the air from one place to another, it travels in the air for a certain distance called the "carry" or "flight," and on coming to the ground again at the end of its "carry" or "flight", it bounces 45 and then rolls along until it stops. For the purpose of this game it is necessary to disregard the bouncing and to consider that after the "carry", the ball rolls along the ground until it stops.

45 50 A topographical map 60 is prepared of an entire golf course. For convenience the map is divided into 9 or 18 sheets (according as the course has 9 or 18 holes) and on each sheet is laid out the playing course for one 55 hole. On the sheet for each hole will be located as previously explained, the teeing ground, the fairway, the green, the cup, the rough and all the hazards on that hole. The sand traps will be numbered with the minimum height ball that can be played to get out of that trap. On either side of the bunkers will be drawn lines for each height ball. These lines will be drawn at a distance from the bunker equal to the minimum distance a ball hit with that height must be from that

bunker in order that the ball shall have attained in the case of an ascending ball, or still have in the case of a descending ball, a sufficient height to clear that bunker.

55 I will assume that any ball that hits a bunker on the "carry" will be stopped by the bunker and roll down the side to the ground. In order to help justify this assumption, I have cut off the top crown of the bunker for the reason that a ball hitting that part may bound over.

60 A ball will be assumed to have no roll in rough grass and a ball rolling over a sand trap will be assumed to fall into that trap.

65 The strip 53 of the protractor is divided and numbered to correspond to the deflection dial 45 on the indicating device. The scale is laid out on the perpendicular line of the protractor and represents units of distance to the same scale as that to which the map is drawn. Having their zero point at the zero point of the scale of the protractor are laid out on the protractor the scales giving the carry for each height ball to the same scale as that of the protractor scale.

70 We now proceed to play the game as follows. Referring to Figure 5, the protractor 50 is laid on the map for the hole, the zero point 51 of the protractor scale being placed and pivoted by a pin on the teeing ground and the line of the perpendicular scale designated O—Z, in Figure 5, being placed by the player on the line along which he wants to hit. In most cases this will be the straight line to the hole, but it may be expedient in the player's opinion to play along some other line to avoid hazards. Having thus placed the protractor 50 the player then hits the ball and reads the distance and deflection on the indicating device i. e. "reading 150 yards 75 deflection 65". The protractor is then rotated until the line of the scale 54 is at this deflection and 150 yards is laid out on the scale at point A¹. There being no hazards between this point A and the teeing ground, this is the point to which the ball has been hit. The protractor or 50 is then placed with its zero point at A¹ and the line of the protractor on the line along which the player 80 wishes to hit, and the ball is hit again. The distance and deflection are again read 125 yards—deflection 65 and this point is laid out as before, but we see that line from A¹ to A² lies over "rough" or long grass. We therefore take the "height" reading on the indicating machine and it is height #3. The protractor is then rotated until the height #3 scale lies on the line A¹—A² and at the 125 yard point on the scale we find that the end of the carry is at A³ and in the rough. Since there is no roll in the rough, the ball 85 has come to rest at A³ at the end of the carry and the next shot is played from the rubber simulation of the resistance offered to the club head Figure 7. The protractor is placed

90 95 100 105 110 115 120 125 130

as before at A³ and the ball is hit again. Reading 70 yards—deflection 45 height 0 (the ball having been hit on top so that it does not leave the ground but only rolls). 5 Inasmuch as there is no roll in the rough that stroke has not advanced the ball and the next stroke is played from the same place and from the rubber simulation of rough or long grass. The ball is hit again reading 10 90 yards—deflection 40 height #4. We lay off this distance and deflection from A³ and as the end of carry as obtained from the height #4 scale lies beyond the rough, the point A⁴—90 yards distant is the point to 15 which the ball has been hit. The protractor is placed at A⁴ and the ball hit again reading 133 yards—deflection 35 height #1. The path of the stroke A⁴—A⁵ is over a sand trap and getting the carry we see that the carry 20 ends before the sand trap and the ball is therefore in the trap at A⁶. The sand trap is marked #3 and the next shot should be played from the sand box Figure 6 with a number height of #3. The protractor is 25 laid at A⁶ and the ball hit. Reading 60 yards—deflection 48—height #2. This shot is not high enough and has not advanced the ball out of the trap. The next shot is played on the same point. Ball is hit reading 30 163 yards—deflection 60—height #3. Laying off this distance and deflection A⁶—A⁷ and getting the carry from the height #3 scale we see that the end of the carry lies between the near edge of the bunker 35 and the #3 line on the further side of the bunker. The ball has therefore hit the bunker on the carry and the next stroke must be played from point A⁸ in the bunker. It must be played with a height one greater 40 than of the line number nearest the bunker or height #4. The protractor is laid at A⁸ and the ball is hit reading 85 yards—deflection 56—#2 height. This is not high enough and the shot has not advanced the ball out of the bunker. The next shot is 45 played again from A⁸ reading 42 yards—deflection 68—height #4. This clears the bunker and there being no other hazard, the ball is now at A⁹. The protractor is then 50 put at A⁹ and the ball hit reading 125 yards—deflection 40—height #3. Thus pointer A¹⁰ lies beyond the brook and from the carry scale for height 3 then see that the carry ends and roll starts before the brook is 55 reached. Therefore the ball is in the brook and the next shot is played from the bank of the brook with the penalty of a stroke for lifting the ball out of the brook. Protractor is put at A¹¹ and ball is hit, reading 70 60 yards—deflection 60—height #2. The brook is carried and there being no other hazards the ball is at A¹² on the green. The remaining distance from A¹² to the hole is then measured and a free ball actually hit into a 65 hole from the distance by using any of the

well known putting devices now on the market.

The player's score for the hole is therefore 12 plus the number of strokes it will take him to hit into a hole from a distance A¹². 70

Having described my invention and its operation what I claim and desire to secure by Letters Patent is:

1. In an instrument for registering the flight of a golf ball, telescopically arranged 75 members movable relatively of one another a distance proportional to a pulling force exerted by one of the members the said members comprising tubular drums arranged one within the other, the outer drum having a series of longitudinal slots cut in its walls, the inner drum being provided with radial lugs adapted to be guided in said slots, means disposed between the drums to counteract the pulling force of the inner drum, an indicator ring longitudinally adjustable over the outer drum, the latter being provided with a scale over which the ring is driven to measure the longitudinal movement of the inner drum 80 and a golf ball connected to the inner drum to provide the pulling force. 85

2. In an instrument for registering the flight of a golf ball, telescopically arranged 90 members movable relatively of one another a distance proportional to a pulling force exerted by one of the members the said members comprising tubular drums disposed one within the other, resilient means

tending to normally hold the drums contracted the outer drum having longitudinal 95 guide slots the inner drum being provided with radially disposed lugs at one end, movable in said slots, a scale disposed on said outer drum to designate the said pulling

force in unit terms, a loosely mounted indicator embracing the said outer drum and adapted to be moved relatively of the said scale by being engaged by the movement of said lugs and a golf ball connected to the inner drum to provide the pulling force. 100 105

3. In an instrument for registering the flight of a golf ball, telescopically arranged 110 members movable relatively of one another a distance proportional to a pulling force exerted by one of the members, a golf ball connected to the said one of the said members to provide the pulling force, and means

disposed between the said golf ball and the members to register the trajectory of the ball through a plane vertically disposed 115 with respect to the axis of said members, the said means comprising a strap pivotally supported at the free end of the member exerting the pulling force, a string attached at one end to the strap and the other to said ball, and means adapted to register the vertical displacement of the ball during flight, substantially as described. 120

4. In an instrument for registering the 125 130

flight of a golf ball, telescopically arranged members movable relatively of one another a distance proportional to a pulling force exerted by one of the members, a golf ball connected to the said one of the members to provide the pulling force, and means adapted to register the direction of flight of the said ball with respect to a horizontal plane, said means comprising a pivotal support for said members, a bracket having a dial adapted to rotate about said support and being connected to one of the said members, relatively movable plates loosely disposed axially of said support and arranged one over the other, both plates being provided with indicators projecting therefrom, and means carried by said dial and movable in an arc to engage one or the other of said indicators to rotate the latter to a degree equal to the horizontal displacement of the ball in its flight, substantially as described.

5. In combination, a measuring instrument of the character described a supporting plate having an upright bearing surface projecting therefrom, a supporting bracket pivotally mounted on said surface and having a dial disposed in an arc and a lug projecting from a zero point in said dial and a socket disposed at the end thereof, rotatable indicator plates loosely mounted on said bearing surface and having projections disposed in the paths of movement of said

lug, a tubular member attached to said socket and provided with longitudinal slots, one of which is provided with transverse 35 graduations along its walls, a telescopically disposed tubular member having lugs slidably mounted in said slots, an indicator ring embracing said first tubular member and adapted to be adjusted by engagement with 40 the said lugs projecting, through said slots, whereby axial movement of the second will advance the indicator ring over the said scale, a spring disposed within the first member and connected to the latter and the 45 other member, a pivoted strap mounted on the free end of said second tubular member, a ball depending from the closed end of said strap, means adapted to connect said strap with a golf ball, the movement of said 50 strap about its pivot being confined to a vertical plane with respect to the axis of the tubular members, a dial carried by the said free end of the second member and disposed on an arc to measure the trajectory of the 55 said ball after a hit is made, and means disposed between the supporting plate and the supporting bracket to maintain the balance of the device on a horizontal plane.

In testimony whereof, I have signed my 60 name to this specification this 26th day of March, 1923.

ALBERT LEVKOWITS.
